UNITED STATES PATENT OFFICE

132,948

DESIGN FOR A BANNER

Mark Cooney, San Francisco, Calif., assignor of one-half to Leo Y. Boocharin, San Francisco, Calif.

Application December 24, 1941, Serial No. 104,820

Term of patent 14 years

To all whom it may concern:

Be it known that I, Mark Cooney, a citizen of the United States, residing at 355 Fulton Street, San Francisco, in the county of San Francisco and State of California, have invented a new, original, and ornamental Design for a Banner, of which the following is a specification, reference being had to the accompanying drawing, forming part thereof.

The figure is a plan view of a banner, showing my new design.

I claim:

The ornamental design for a banner, as shown.

MARK COONEY.
